(57) **CLAIM**

We claim the ornamental design for a pleated pediatric medical mask with selectively formable metal strip insert for conforming to nose, as shown and described.

DESCRIPTION

FIG. 1 is a perspective view of a pleated pediatric medical mask with selectively formable metal strip insert for conforming to nose showing our new design;

FIG. 2 is a reduced front elevational view thereof;

FIG. 3 is a reduced rear elevational view thereof;

FIG. 4 is a an end elevational view thereof, the elevational view of the opposing end being a mirror image thereof;

FIG. 5 is a reduced top plan view thereof; and,

FIG. 6 is a reduced bottom plan view thereof.
